(57) **CLAIM**

The ornamental design for a “dryerball,” as shown and described.

DESCRIPTION

FIG. 1 is a perspective view of a dryerball, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a perspective view of a second embodiment of the dryerball;

FIG. 8 is a front elevational view thereof;

FIG. 9 is a rear elevational view thereof;

FIG. 10 is a left side elevational view thereof, the right side elevational view being a mirror image thereof;

FIG. 11 is a top plain view thereof; and,

FIG. 12 is a bottom plain view thereof.

The phantom lines shown in FIGS. 1, 2 4 , 5, 7, 8, and 10 are for illustrative purposes only and form no part of the claimed design.
